G. C. THOMPSON

PITCHER OR ANALOGOUS ARTICLE

Filed May 6, 1926

FIG. 1.

FIG. 2.

Inventor

George C. Thompson

By A. S. Patterson

Attorneys

UNITED STATES PATENT OFFICE.

GEORGE C. THOMPSON, OF EAST LIVERPOOL, OHIO, ASSIGNOR TO THE C. C. THOMPSON POTTERY CO., OF EAST LIVERPOOL, OHIO.

DESIGN FOR A PITCHER OR ANALOGOUS ARTICLE.

Application filed May 6, 1926. Serial No. 17,591. Term of patent 7 years.

To all whom it may concern:

Be it known that I, GEORGE C. THOMPSON, a citizen of the United States, residing at East Liverpool, in the county of Columbiana, and State of Ohio, have invented a new, original, and ornamental Design for a Pitcher or Analogous Article, of which the following is a specification, reference being had therein to the accompanying drawings.

My invention relates to a new and ornamental design for a pitcher, or analogous article, as shown in the accompanying drawing.

The predominant feature of the design is the angular effect given to the article by providing a plurality of flat surfaces arranged at angles to one another. The an-

gular effect is also carried out in the handle of the article.

A raised ornamental design is placed on the pitcher adjacent its upper edge and completely encircles the same below the handle and the pitcher spout.

In the drawings:

Figure 1 is a view in side elevation of the article, showing my new design.

Figure 2 is a top plan view thereof.

I claim:

The ornamental design for a pitcher or analogous article, as shown and described.

In testimony whereof, I hereunto affix my signature.

GEORGE C. THOMPSON.
